(57) **CLAIM**

The ornamental design for a work glove, as shown and described.

DESCRIPTION

FIG. 1 is a perspective view of the work glove in accordance with the present invention;

FIG. 2 is a plan view of the work glove of FIG. 1;

FIG. 3 is a side view of the work glove of FIG. 2;

FIG. 4 is a second side view of the work glove of FIG. 2;

FIG. 5 is a first end view of the work glove of FIG. 2; and,

FIG. 6 is a second end view of the work glove of FIG. 2.

The broken lines showing a glove illustrate portions of the work glove and form no part of the claimed design. The double rows of broken lines within the claimed portion of the design represent stitching and form part of the claimed design.

1 Claim, 3 Drawing Sheets
